TREATMENT OF HYDROCARBONS

Harold V. Atwell, White Plains, N. Y., assignor to
 Gasoline Products Company, Inc., Newark, N. J.,
 a corporation of Delaware

Application July 25, 1933, Serial No. 682,059

5 Claims. (Cl. 196—9)

My invention relates to the treatment of hydrocarbons, more particularly hydrocarbon oils and hydrocarbon gases containing unsaturated constituents such as olefins, and my invention has for objects the provision of a process of effecting inter-reaction between such hydrocarbon oils and gases and the recovery of valuable products therefrom, as well as such further improvements in operative advantages and results as may herein-after be found to obtain.

With these objects in view, my invention contemplates contacting gaseous olefins or the like with normally liquid hydrocarbons containing unsaturated, aromatic or naphthenic hydrocarbon constituents, such, for example, as so-called "pressure tars" and other residual oils produced in the pyrolytic decomposition of petroleum, petroleum oils or the like, the contact taking place at elevated temperatures in the presence of limited quantities of oxygen or gases containing same, with the result that inter-reaction between the various hydrocarbons takes place resulting in the formation of valuable oils of intermediate boiling points compared to the hydrocarbons initially employed.

While the nature of the reaction or reactions taking place, due in part to the complex nature of the hydrocarbon materials present, is obscure and my invention is not to be considered as limited in scope by any particular theory of the nature of such reaction, it is believed that certain hydrocarbons which are present in tars and other residual oils of the character set forth are partially dehydrogenated by the oxygen, forming compounds which are highly reactive and combine readily with other unsaturated hydrocarbons such as gaseous olefins, to form hydrocarbon oils of intermediate boiling points suitable for use either as such or after suitable pyrolysis in the preparation of motor fuel or gasoline.

Thus I may subject gaseous olefins or gases containing the same to contact at elevated temperature, preferably at a temperature within what may be designated as a range suitable for the cracking of hydrocarbon oil, for example, from 750° to 1000° F., and under elevated pressure, with residual or other hydrocarbon oils of the character set forth, in the presence of limited quantities of oxygen or gases containing the same, the resultant products of reaction being removed and fractionated as desired to recover normally liquid hydrocarbon products therefrom.

My invention further contemplates a method wherein hydrocarbon gases or oil may be cracked in such manner as to produce a mixture of hydro-

carbons containing cracked constituents including unsaturated hydrocarbons, together with small quantities of oxygen, the mixture of gases or vapors thus obtained being brought into contact with hydrocarbon liquid containing reactive hydrocarbon constituents at elevated pressure and temperature, and the products being fractionated as desired.

In one aspect, my invention contemplates a process in which gases resulting from the combustion of a suitable fuel are reduced in temperature to a suitable point and brought into contact with hydrocarbon gas or oil to crack the same, the resultant mixture of gases or vapors, products of combustion and, it may be, oxygen, being further reduced to a temperature of for example 750° to 1000° F. and contacted at that temperature with residual oil or tar, with or without the introduction of additional quantities of oxygen or oxygen-containing gases as desired, the products of reaction being fractionated as indicated hereinabove.

In order that my invention may be clearly set forth and understood, I now describe, with reference to the drawings accompanying and forming a part of this specification, a preferred manner in which my invention may be practiced and embodied. In these drawings,

Figure 1 is a more or less diagrammatic view, partly in elevation and partly in vertical section, of apparatus for treating hydrocarbons in accordance with my present invention; and

Figure 2 is a similar view of an alternative form of apparatus for carrying out my process.

Similar reference numerals designate similar parts in both views of the drawings.

Referring now to the drawings, there is shown an apparatus comprising in part a refractory-lined furnace or combustion chamber 1, a refractory-lined cracking chamber 2, a reaction chamber 3, a dephlegmator 4, a fractionating tower 5, and a gas separator 6. The reaction chamber 3 may be empty or provided with gas-and-liquid-contact devices commonly used in the oil-crack-
 ing art.

A suitable fuel such as oil or gas is introduced to a burner 7 located in the combustion chamber 1 through an inlet 8 having a pump 8a and valve 9, while air for combustion of the fuel is introduced to the burner 7 through a valved inlet 10. The proportions of fuel and air may be adjusted to give substantially complete combustion or to provide an excess of air over that required for the combustion of the fuel. The products of combustion leave the combustion chamber 1 and

are passed through a refractory-lined duct 12 to the cracking chamber 2.

It is sometimes desirable to reduce the temperature of the products of combustion to about 1500° F. before entering the cracking chamber 2 and for this purpose I provide a valved inlet pipe 13 for steam or other diluent gas, and a valved inlet pipe 14 for air or oxygen, both of which pipes conveniently communicate with the duct 12, as shown. Any of these gases, or a mixture thereof, may be admitted to the products of combustion in such amount as to reduce the temperature thereof to about 1500° F. Where air or oxygen is admitted at this point, the amount of the same admitted is such as to effect combustion of any combustible constituents such as carbon monoxide, which may remain in the gases of combustion leaving the combustion chamber, and preferably also to provide a small amount of free oxygen in the gases entering the cracking chamber 2.

In the instance illustrated in Figure 1, the gases entering the reaction chamber 2 through the duct 12 pass upward through an interiorly disposed duct 15 to the top of the reaction chamber 2 and then downward through a chamber 16, within which I may provide bodies 17 of checkerbrick or other refractory and heat-accumulative material.

Hydrocarbon gas or oil of suitable character is introduced into the cracking chamber 16, to be cracked by direct contact with the hot gases passing through the latter. In the instance shown in Figure 1, I provide valved gas inlets 18 and 19 communicating with the interior of the chamber 16.

The mixture of hydrocarbons, gases of combustion, and it may be excess oxygen and steam or other diluent gas, transverse the cracking chamber 16 at a temperature of from 750° to 2500° F., the time of contact being so controlled as to effect material cracking of the hydrocarbon gas, resulting in the formation of unsaturated hydrocarbons, such as gaseous olefins or other reactive compounds. The products then pass through a conduit 21 into the reaction chamber 3.

At this point, additional quantities of air or other oxygen-containing gas or diluent gas may be introduced through a valved inlet 22 communicating with the conduit 21, while additional quantities of gaseous olefins or gases containing the same, such for example as gases produced in the cracking of hydrocarbon oils, may be introduced through a valved inlet 23 communicating with the reaction chamber 3.

Irrespective of whether excess oxygen beyond that required for combustion of the fuel introduced at the burner 7 is introduced at 10, at 14, or at 22, the process is preferably so conducted that the mixture of gases entering the reaction chamber 3 contains free oxygen. The introduction of air or oxygen-containing gas is so regulated as to provide a volume of oxygen less than that of the hydrocarbon gases or vapors present, and preferably equal to from 20 to 50 percent of the volume of the hydrocarbon gases and vapors. It will, of course, be readily understood that the specific ratios employed will vary with the nature of the hydrocarbons, the temperature and the nature of the results desired. It will further be obvious to those skilled in the art that explosive mixtures of oxygen-containing gases and hydrocarbons are to be avoided.

Excess oxygen admitted to the system prior to the introduction of the gases of combustion into the cracking vessel 2 may be consumed wholly or

in part by reaction with the hydrocarbon gases or oil introduced into the latter, thus requiring the addition of further quantities of oxygen at 22.

By means of a pipe 24, I introduce into the mixture of gases entering the upper portion of the reaction chamber 3 a suitable hydrocarbon liquid, preferably one containing a considerable amount of unsaturated, aromatic or naphthenic hydrocarbon constituents. Various heavy oils obtained in the pyrolytic decomposition of hydrocarbon oils, and preferably residual oils or tars high in reactive constituents, may be employed.

Through contact with the hot gases entering the reaction chamber 3, which gases contain such unsaturated hydrocarbons as gaseous olefins or the like together with small quantities of free oxygen, constituents of the liquid introduced through the conduit 24 are caused to react with hydrocarbon gases within the reaction chamber 3 resulting in the formation of hydrocarbons of intermediate boiling points.

Preferably, the temperature within the reaction chamber 3 is maintained within a range of from about 750° to about 1100° F. Where the temperature of the gases leaving the cracking chamber 16 is considerably above this range, cooling may be effected by means of gas or liquid introduced through the inlets 22, 23 and 24, respectively, as will be readily understood by those skilled in the art.

While, as indicated hereinabove, I do not rely upon any particular theory as to the nature of the reaction taking place in the chamber 3, nevertheless it is probable that the oxygen present effects a limited dehydrogenation of the hydrocarbon liquid or unsaturated constituents thereof, the resultant highly active products of reaction combining with gaseous olefins or otherwise polymerizing or reacting in the presence of the cracked hydrocarbons entering the reaction chamber 3 through the conduit 21 to form products of intermediate boiling points.

The reacting materials in the chamber 3 may be maintained under a substantially atmospheric pressure. Preferably, however, they are maintained under an elevated pressure, for example, from 50 to 200 pounds per square inch, or even higher if desired, and the same or higher pressures may be maintained in the chambers 1 and 2.

The gases and vapors reaching the bottom of the reaction vessel 3 are withdrawn therefrom through a conduit 30 having a valve 31, and may pass to the dephlegmator 4, or through a branch line 32 having a valve 33 directly to the fractionating tower 5. Ordinarily, however, I prefer to pass the gases and vapors through the dephlegmator 4 before admitting them to the fractionating tower 5. The dephlegmator 4 is preferably provided with a plurality of baffles 35 and an inlet 36 for introducing a suitable reflux oil.

The liquid products of reaction are withdrawn from the reaction vessel 3 through an outlet 37 having a valve 38, while liquid products from the dephlegmator 4 are withdrawn therefrom through an outlet 39 having a valve 40 and leading to a pump 41. The former may be run to storage through a branch line 42 having a valve 43, or may be delivered to the pump 41 through a branch line 44 having a valve 45.

The heavy liquid products removed from the reaction vessel 3 and/or those removed from the dephlegmator 4, may be delivered in part or in whole to the reaction vessel 3 through a conduit 46, a branch line 47 having a valve 48 and the

inlet 24, or to the burner 1 through a branch line 49, having a valve 50, and the conduit 8. The partially dephlegmated vapors from the dephlegmator 4 and/or the vapors from the conduit 32 pass through a conduit 52 to the lower part of the fractionating tower 5, which is provided with a plurality of plates or trays 53 of suitable design, as well as an inlet 54 for admitting reflux oil. By means of cooling effected by the addition of reflux to the tower 5 or otherwise, the vapors passing up through the latter are fractionated, conditions being preferably so regulated as to recover a fraction of the nature of a gas oil which collects in the bottom of the tower 5, from which it is withdrawn by means of a conduit 55 having a valve 56 and leading to a pump 57.

A portion of this gas-oil fraction may be withdrawn through the line 36, wherein is located a valve 58, and delivered to the dephlegmator 4. This portion of the gas-oil fraction may be cooled, if desired, before introducing it into the dephlegmator 4.

The gases and uncondensed vapors withdrawn from the top of the tower 5 pass through a vapor line 60 to a condenser 61, and thence through a line 62 to the gas separator 6. Condensate, comprising a low boiling hydrocarbon liquid of the naphtha or gasoline type, is withdrawn from the separator 6 through a conduit 63 having a valve 64. A portion of the condensate may be returned as reflux to the tower 5 through the line 54, which is provided with a valve 65 and a pump 66 for this purpose.

Uncondensed gases are removed from the separator 6 through a conduit 67 having a valve 68, and may be disposed of as desired. Due to the relatively high proportion of incondensable gases passing through the system, it may often be desirable to scrub the gases from the separator 6 with a suitable solvent, for the recovery of valuable light constituents therefrom, and for this purpose I provide a scrubber 70 having an inlet 71 and an outlet 72 for a suitable solvent, such as cool gas oil or other hydrocarbon oil. The scrubbed gases, consisting almost entirely of fixed gases and gaseous products of combustion, escape from the scrubber 70 through an outlet 73 and may be disposed of as desired. The enriched oil withdrawn through the outlet 72 may be treated in any suitable manner for the recovery of absorbed constituents therefrom.

In Figure 1 I have also illustrated apparatus for employing excess heat generated within the combustion chamber 1 for the purpose of effecting a preliminary distillation or cracking of oil, for example a crude petroleum or a reduced crude, whereby such oil may be treated for the recovery of various constituents thereof, one or more of such constituents being employed in those portions of the apparatus described hereinabove.

Thus, in Figure 1, I have illustrated pipe coils 80, 81 and 82 located within the combustion chamber 1 in such manner as to be heated by the combustion of fuel introduced in the burner 1. The location of the coils 80, 81 and 82 within the combustion chamber 1 is preferably such that the coil 80 is subjected to the highest heat, coil 82 to the lowest heat, while coil 81 is subjected to an intermediate degree of heat.

When heavy oil or tar is to be introduced from an outside source into the reaction chamber 3, it may first be delivered by a pump 83 through a conduit 84 to the coil 82, where it is heated to a temperature short of a cracking temperature, for

example, from 400° to 600° F., or even to a cracking temperature of, for example, from about 750° to 1000° F. The resultant heated products are then discharged through conduits 85 and 86 and the inlet 24 to the reaction chamber 3.

The coils 80 and 81 may also be used for a similar purpose and in the specific instance illustrated in Figure 1 are employed for the cracking of a suitable oil such as gas oil, for example, gas oil recovered in the fractionating tower 5. Such gas oil may be delivered to the coils 81 and 80 by means of the pump 57 and a conduit 90, while additional gas oil may also be supplied to the coils 81 and 80 through a conduit 91. In this instance, I provide a reaction vessel 92, a primary dephlegmator 93 and a fractionation tower 94. Fresh oil, for example, a crude petroleum or a reduced crude is introduced to the system by means of a pump 95 through a conduit 96 to pass through a heat-exchange coil 97 located in the upper portion of the fractionating tower 94, and after leaving the fractionation tower 94 passes through a conduit 98 to be discharged into the interior of the dephlegmator 93, the interior of which is provided with baffles 99.

In the dephlegmator 93, the heated charge oil is subjected to direct contact with hot vapors passing from the reaction vessel 92 through a vapor line 101 into the bottom of the dephlegmator 93, and a combined dephlegmating and distilling action takes place. Residual portions of the charge oil, together with condensed portions of the vapors entering the dephlegmator 93, are withdrawn from the bottom of the dephlegmator 93 through a conduit 102 having a valve 103, to be discharged through the conduit 86 and an inlet 24 into the reaction chamber 3. However, a portion or all of the liquid collecting in the bottom of the dephlegmator 93 may be withdrawn through a branch conduit 104 having a valve 105 and a pump 106, by means of which this oil may be delivered to the reaction vessel 92. Vapors reaching the top of the dephlegmator 93 pass through a conduit 107 to the bottom of the fractionating tower 94, the interior of which is provided with suitable plates or trays 108, and in which, due to the cooling effect of the oil passing through the heat-exchange coil 97, a dephlegmating and fractionating action takes place.

This action is so regulated as to permit the recovery at the base of the fractionating tower 94 of a stock suitable for cracking, for example gas oil, which is then delivered through a valve 110 and a pump 111 to the conduit 91 to be supplied to the coils 81 and 80. In the latter the gas oil is heated to a cracking temperature of, for example, from 750° to 1050° F. under a suitable pressure of, for example, from 50 to 1000 pounds per square inch. The hot cracked products from the coil 80 pass through a transfer line 113 to the reaction vessel 92 where they may be joined by liquid removed from the base of the dephlegmator 93. In the reaction vessel 92 a partial separation into vapors and liquid occurs, the vapors passing through the conduit 101 into the dephlegmator 93 as stated hereinabove, while the liquid is withdrawn through a conduit 115 having a valve 116 to be delivered through the conduit 86 on the inlet 24 to the reaction vessel 3.

The vapors and gases remaining uncondensed at the top of the fractionating tower 94 pass through the vapor line 120 to a condenser 121 and thence through a conduit 122 to a gas separator 123, from which liquid condensate comprising naphtha or gasoline may be removed 75

through a pipe 124 having a valve 125. Gases leave the separator 123 through a conduit 126 having a valve 127 and may either be taken off through a branch conduit 128 having a valve 129 or may be permitted to flow through the conduit 126 and the inlet 23 to the vessel 3.

When these gases are insufficient or unsuitable for the purpose in view, additional gas may be introduced from an outside source through a conduit 132 having a valve 133 and provided with a pump or fan 134 and leading to the inlets 18 and 19. Various gases may be employed for this purpose, such, for example, as methane, ethane, propane, butane, ethylene, propylene and other hydrocarbon gases or mixtures of these, such as natural gas and refinery gas.

In general, of course, it is desired to introduce gases containing considerable amounts of unsaturates to the vessel 3; such gas may be obtained from the separator 123, especially when the cracking effected in the coil 80 and chamber 92 is of the high temperature vapor phase type, or gas from an outside source may be employed as indicated.

It will be obvious that, while I have illustrated coils 80, 81 and 82 located within the combustion chamber 1, these heating coils may be located in a separate furnace if so desired, especially where it is desired to maintain the combustion chamber 1 under higher pressure. Moreover, when the coils 80, 81 and 82 are located within the combustion chamber 1, it may be desirable to provide more heat at this point than is required for the cracking and reaction taking place in the vessels 2 and 3. For the purpose of removing part of the gases of combustion leaving the combustion chamber 1, the vessel 2 is provided with a stack 140 having a valve 141, whereby a suitable portion of the gases reaching the top of the vessel 2 may be bled off to the atmosphere without being permitted to pass through the chamber 16 and the subsequent apparatus.

In Figure 2, I have illustrated a modified form of apparatus which is especially suitable for use when very high pressures and temperatures are to be employed. As shown in this figure, the apparatus comprises a metal shell 150 of more or less cylindrical shape, the interior of which is divided by means of a refractory liner 151 into a combustion chamber 152, a cracking chamber or passageway 153, and a reaction chamber 154.

Fuel and air are admitted to a burner 155 located in the combustion chamber 152 through valved inlets 156 and 157, respectively, the combustion being controlled to produce gases of combustion having a limited amount of free oxygen.

As the gases of combustion pass from the combustion chamber 152 into the passageway 153, they are brought into direct contact with a suitable hydrocarbon gas or oil introduced through an inlet pipe 158 having a valve 159. A pyrolysis or cracking of the hydrocarbon gas or oil takes place, resulting in the formation of unsaturated hydrocarbons, mainly of a normally gaseous character, for example, gaseous olefins and the like. The mixture of cracked gases and vapors then passes into the reaction chamber 154 where it is brought into contact with hydrocarbon oil, such, for example, as residual oil or "pressure tar" containing substantial quantities of reactive constituents, this oil or tar being introduced through an inlet pipe 161 having a valve 162.

Within the reaction chamber 154, which is preferably provided with a baffle 163, the cracked gases and hydrocarbon oils are caused to react in the

manner set forth hereinabove, the introduction of oil or tar being preferably in sufficient amount to reduce the temperature of the cracked gases and vapors from a passageway 153 to, for example, from 800° to 1000° F. The resultant vapors and residual liquid may be separately withdrawn through valved outlets 164 and 165, respectively, or may be withdrawn together through a valved outlet 166. In the former instance, the gases and vapors withdrawn through the conduit 164 are fractionated in the usual manner while the liquid withdrawn through the outlet 165 may be flashed or otherwise treated to recover valuable constituents therefrom, while in the second instance the combined gases, vapors and liquids drawn through the outlet 166 may be delivered to a separating chamber before being fractionated in the usual manner.

In this instance, pressure of from 50 to 200 pounds or even higher may be maintained within the shell 150 and the temperatures in the combustion chamber may vary from around 1000° F. to as high as 2500° F., the latter temperatures being desirable when times of contact of the gas or oil introduced through the inlet 158 are extremely short. With longer times of contact lower temperatures approaching 1000° F. may be employed. If the oil or tar introduced through the inlet 161 is insufficient in amount to accomplish the desired quenching effect, an additional quenching medium, such for example as steam or inert gas, may be introduced along with the oil or tar through the inlet 161.

The apparatus illustrated in Figure 2 may be substituted for that portion of the apparatus shown in Figure 1 which is intended to perform the same functions, and any of the various expedients illustrated in Figure 1 may be employed in conjunction with the apparatus illustrated in Figure 2. For example, the residual liquid withdrawn from the reaction vessel 154 may be employed as a fuel or may be recycled to the inlet 158.

Furthermore, while I have illustrated in Figure 1 a specific form of oil-cracking apparatus, it will be obvious that this apparatus may vary considerably in character, and that my invention may be employed in conjunction with many types of cracking apparatus for producing the oils or tars and gases to be used in my process.

It will therefore be apparent to those skilled in the art that my invention is not limited to the specific examples given hereinabove by way of illustration, but may variously be practiced and embodied within the scope of the claims hereinafter made.

I claim:

1. The process of effecting thermal conversion of hydrocarbons which comprises passing a hydrocarbon oil through a cracking zone and there subjecting it to an elevated temperature effective to crack said oil, separating vaporous and residual conversion products, fractionating the vapors to separate a gasoline fraction, a higher-boiling fraction and uncondensed gases, contacting said gases with said residual conversion products at a temperature of from 750° to 1100° F. in the presence of a limited amount of free oxygen, fractionating resultant vaporous products of reaction to recover another gasoline fraction and another higher-boiling fraction, and delivering said other higher-boiling fraction to said cracking zone for further conversion.

2. The process of effecting thermal conversion of hydrocarbons which comprises passing a hy-

drocarbon oil through a cracking zone and there subjecting it to an elevated temperature effective to crack said oil, separating vaporous and residual conversion products, fractionating the vapors to separate normally liquid constituents from uncondensed gases, contacting said gases with said residual conversion products at a temperature of from 750° to 1100° F. in the presence of a limited amount of free oxygen, fractionating resultant vaporous products of reaction to recover normally liquid products therefrom including materials having boiling points above a gasoline boiling point range, and delivering at least a portion of the thereby recovered normally liquid products having boiling points above a gasoline boiling-point range to said cracking zone for further conversion.

3. The process of effecting thermal conversion of hydrocarbons which comprises subjecting a hydrocarbon oil to an elevated temperature effective to crack said oil, separating vaporous and residual conversion products, fractionating the vapors to separate normally liquid constituents from uncondensed gases, cracking said gases at a temperature in excess of 1300° F. to form gaseous olefins, contacting resultant cracked olefinic gases with said residual conversion products at a temperature of from 750° to 1100° F. in the presence of a limited amount of free oxygen, and fractionating the resultant products of reaction to recover normally liquid products therefrom.

4. The process of effecting thermal conver-

sion of hydrocarbons which comprises passing a hydrocarbon oil to a cracking zone and there subjecting it to an elevated temperature effective to crack said oil, separating the vaporous and residual conversion products, fractionating the vapors to separate a gasoline fraction, a higher-boiling fraction and uncondensed gases, contacting said gases with cracked residual hydrocarbon oil at a temperature of from 750° to 1100° F. in the presence of a limited amount of free oxygen, fractionating resultant vaporous products of reaction to recover another gasoline fraction and another higher-boiling fraction, and delivering at least a portion of said other higher-boiling fraction to said cracking zone for further conversion.

5. The process of effecting thermal conversion of hydrocarbons which comprises passing a hydrocarbon oil through a cracking zone and there subjecting it to an elevated temperature effective to crack said oil, separating vaporous and residual conversion products, fractionally condensing the vapors to recover gasoline therefrom, contacting said residual conversion products with unsaturated hydrocarbon gases at a temperature of from 750° to 1100° F. in the presence of a limited amount of free oxygen, fractionating resultant vaporous products of reaction to recover another gasoline fraction and another higher-boiling fraction and delivering at least a portion of said other higher-boiling fraction to said cracking zone for further conversion.

HAROLD V. ATWELL.
